UNITED STATES PATENT OFFICE.

CHARLES M. STONE AND WILLIAM H. SPENCER, OF LEWISTON, MAINE, ASSIGNEES OF
ONE-THIRD TO WILLIAM H. PUTNAM, OF LEWISTON, MAINE.

SHUTTLE.

Application filed September 4, 1925. Serial No. 54,537.

To all whom it may concern:

Be it known that we, CHARLES M. STONE and WILLIAM H. SPENCER, citizens of the United States, residing at Lewiston, in the 5 county of Androscoggin and State of Maine, have invented certain new and useful Improvements in Shuttles; and we do declare the following to be a full, clear, and exact description of the invention, such as 10 will enable others skilled in the art to which it appertains to make and use the same.

Our invention relates to improvements in shuttles and more particularly those now employed in the weaving of rayon or artificial silk.

At the present time, quantity weaving of this artificial silk on automatic looms is impossible because the filling shells off, that is, it forms wads and becomes matted and does 20 not feed evenly from the bobbin. In attempting to overcome this objection, flannel, sheep skin and different kinds of fur have been placed upon the sides and bottom and while being effective to a limited degree, 25 the arrangement prevents doffing out an empty bobbin and replacing it with a full one on an automatic machine. Therefore, these bobbins must be replaced manually, with the result that imperfect cloth is produced, and even though imperfect, quantity 30 production is not possible.

We have overcome the above faults through fixing to the inner sides or walls of the bobbin chamber tufts of bristles or 35 brushes which are spaced along said walls and arranged oblique to the longitudinal center of the shuttle and so engaged with the filling as to prevent shelling or wadding and at the same time permit ready 40 feeding.

With the foregoing in view, the invention resides in the novel subject matter herein-after described and claimed, the description being supplemented by the accompanying 45 drawing.

Figure 1 is a plan view of a shuttle provided with our improved tensioning device;

Figure 2 is a side elevation thereof;

Figure 3 is a sectional view taken substantially on the line 3—3 of Fig. 2; and

Figure 4 is a sectional view taken substantially on the line 4—4 of Fig. 3.

In the accompanying drawing, we have illustrated a conventional form of shuttle comprising a body 1 having the usual bob-

bin-receiving chamber 2 at one end of which is mounted a spring bracket 3 for supporting the bobbin or spindle upon which the filling is wound. This bobbin may be readily removed from the chamber 2 and when in the position shown in Fig. 1, the filling or thread carried thereby may be unwound and threaded through the usual eyelets or ways 5 to the weaving machinery.

While other means may be employed for mounting the set of tensioning devices within the bobbin chamber 2, we preferably employ the structure shown. This preferred type consists in providing the opposed walls of the shuttle 1 with sockets or recesses 6 arranged oblique to the longitudinal center of the shuttle for mounting tufts or bristles 7 whose outer end portions 8 bear lightly upon the filling or thread carried by the bobbin 4. Due to the oblique arrangement of the openings in which the base portions of the bristles are fixed, the outer end portions of the tufts 7 will be inclined substantially in the direction in which the thread travels while being unwound in consequence of which the resistance to the unwinding of the thread will be negligible, yet the pressure will positively prevent shelling or wadding.

By reference to Fig. 4, it will be noted that the bristles 7 are arranged in different planes so that they engage opposite faces of the bobbin or filling carried thereon. In actual practice, we have found that the greater tension should be exerted upon the lower face of the filling, in consequence of which we provide two longitudinal rows of these tufts of bristles which are preferably although not necessarily arranged in staggered or zig-zag relation.

We have conducted extensive experiments in different arrangements of these tufts of bristles and have found that only through arranging them as illustrated can we obtain the desired results, that is they should be separated into tufts spaced apart slightly and inclined for engagement with the filling. Through spacing the tufts of bristles longitudinally and inclining them at substantially the angle illustrated, wadding or shelling of the filling or thread is absolutely eliminated and hence the emptied bobbins may be readily replaced with full ones as is usual in the automatic looms. We are aware of certain prior patents which embody elements

designed to exert tension upon a filling carried by a bobbin but find that none of these devices will operate to effectively prevent shelling or wadding of this new fibre rayon or artificial silk.

Excellent results have been obtained from the details disclosed and they are therefore preferably followed, but within the scope of the invention as claimed, other structures 10 may well be used to advantage. It is obvious that these tufts of bristles may be mounted within the bobbin chamber in many other ways.

We claim:

15 1. A shuttle including a bobbin chamber having opposed side walls, a filling receiving bobbin in said chamber, a single row of longitudinally spaced tufts of bristles extending obliquely into the chamber in the 20 direction of discharge of filling, said tufts being arranged near the upper edge of one wall to yieldably contact with filling, and a pair of parallel rows of longitudinally spaced tufts of bristles extending in the 25 same direction as the first named tufts and arranged adjacent the lower edge of the other side wall for yieldable pressure upon a portion of the filling to one side of a ver-

tical line and below a horizontal line intersecting the vertical line at the axis of the 30 bobbin.

2. A shuttle including a body having a receiving chamber, resilient means to yieldably exert pressure upon the filling, and additional resilient means circumferentially 35 spaced from and of greater strength than the first named means to yieldably exert additional and greater pressure upon a portion of the filling circumferentially spaced from the portion thereof engaged by the 40 first named means.

3. A structure as specified in claim 2; said means comprising longitudinal rows of bristles projecting inwardly from the shuttle 45 bobbin.

4. A structure as specified in claim 2; said means comprising rows of longitudinally spaced tufts of bristles extending obliquely into the chamber in the direction of discharge of filling, said rows extending substantially the entire length of the bobbin. 50

In testimony whereof we have hereunto affixed our signatures.

CHARLES M. STONE.
WILLIAM H. SPENCER.
